C. SCHMIDT

CURTAIN AND SHADE POLE FIXTURE

Filed Sept. 11, 1922

Patented July 10, 1923.

1,461,255

UNITED STATES PATENT OFFICE.

CHARLES SCHMIDT, OF CLIFTON, NEW JERSEY.

CURTAIN AND SHADE POLE FIXTURE.

Application filed September 11, 1922. Serial No. 587,273.

To all whom it may concern:

Be it known that I, CHARLES SCHMIDT, a citizen of the United States, residing at Clifton, in the county of Passaic and State 5 of New Jersey, have invented certain new and useful Improvements in Curtain and Shade Pole Fixtures, of which the following is a specification.

This invention relates to improvements in 10 combined curtain and shade pole fixtures or support brackets as used in dwellings, offices and like places where it is desired to partially prevent the passage of light, as at the windows of the building, by draperies more 15 or less dense and opaque.

The principal purpose of the invention is to produce a simple and efficient type of hanger for receiving the ends of the supporting poles, the hangers being suited to 20 receive fastening means for attachment to walls adjacent the openings to be obscured.

Another object is to provide means by 25 which the pole carrying elements may be adjusted transversely of the window opening, upon fixed backing elements and secured at any point therealong, to suit the length of the poles used.

A further aim is in the provision of an 30 integral spring detent on the slideable element, the same co-operating with a rack formed in the stationary element, in addition to a clamping means associated with both elements.

These objects are attained by the novel 35 construction and arrangement of parts hereafter described and shown in the accompanying drawing, forming part of this disclosure, and in which:—

Figure 1 is a perspective view showing a 40 pair of hangers made in accordance with the invention and showing their application to a conventional type of window.

Figure 2 is a side view of the hanger.

Figure 3 is a front elevational view of the 45 same.

Referring more in detail to the drawing, particularly to Figure 1, the wall of the building is designated by the numeral 10 and the window frame set therein by 11, the 50 same carrying the upper and lower sashes, respectively 12 and 13.

At the upper corners of the window frame 11, in a level plane, are secured elongated rectangular plates 14, provided with openings 55 15 to receive attaching screws or like fasteners, in a manner well understood, and

each of the longitudinal edges, that is to say the upper and lower, are flanged outwardly towards the front as at 16 and 17.

Said flanges form guides for flat plates 60 18, resting against the base plates 14 and provided with central longitudinal slots 19 for the reception of bolts 20, having their heads fixed in the plates 14 near their centers and being provided with thumb nuts 21 65 impinging upon the outer surfaces of the plates 18.

The outer ends of the slide plates may be 70 curved or bevelled as shown, and attached to their inner ends, by rivets 22, are the transverse feet 23 of the brackets 24 having recesses 25 containing slots 26 to receive the pintles of the shade rollers (not shown) as will be apparent.

The curtain pole rests in U-shaped loops 75 27, formed by bending narrow metal strips 28 offset outwardly and twisted at a right angle near their lower ends 29 which are secured by rivets 30 to the bracket elements 24 as is clearly shown.

As shown in Figure 3, the lower flange 17 of the stationary base plate is cut to present a plurality of teeth 31, uniformly spaced like a rack and adapted to receive a detent 32 at the end of an arm 33 formed integral 85 with the slide plate 18 by the slot 34, the plate being recessed as at 35 to provide a thin resilient effect in the arm.

Thus in addition to the clamping effect of the screw 20 and its associated nut 21, the 90 slide plate is held in longitudinal adjustment by the spring detent 32, but in such manner that upon relaxing the nut, the slide may be manually moved relative to the base by the exertion of moderate force, thus 95 providing ready and positive means for adjusting the distances between the pair of hangers to suit any reasonable variation in the length of the shade roller or curtain pole.

Having thus described my invention and set forth the manner of its application, what I claim as new and desire to secure by Letters Patent, is:—

1. A shade hanger bracket comprising a 100 plate having cut turned flanges on its upper and lower edges, a slide operable between said flanges, said slide having a longitudinal slot closed at each end the outer end of said slide being bevelled outwardly to accommodate the slot, a bolt fixed centrally in said base plate passing through the slot, a 110

thumb nut engaging said bolt on the outer side of said slide, an angular bracket fixed on the inner end of said slide, said bracket being adapted to engage a shade roller pintle, an open looped support secured to said bracket to receive one end of a curtain pole, and an integral spring arm formed on said slide to make resilient contact with one of said out-turned flanges.

10 2. A shade hanger comprising a base plate having out-turned flanges on its upper and lower edges, a slide operable between said flanges, said slide having an enclosed longitudinal slot, the outer end of said slide

being bevelled to accommodate the slot, a bolt fixed centrally in said base plate passing through the slot, a thumb nut engaging said bolt on the outer side of said slide, an angular bracket fixed on the inner end of said slide, said bracket being adapted to engage a shade roller pintle, teeth formed in the lower flanges of said base plate, and a spring detent integral with said slide adapted to engage in the spaces between said teeth.

25 In witness whereof I have affixed my signature.

CHARLES SCHMIDT.
